Ms. 782

Edward J. Delany of Philadelphia, Pa. Assort,
Letters Patent No. 82, Dated April 13, 1856.

The schedule referred to in these Letters Patent, and making part of the same,
To all to whom these Presents shall Come:

Be it known, that I, Edward J. Delany
of Philadelphia, in the County of Philadelphia, and
State of Pennsylvania, have invented a new design
for Gas Oven, and that the following is a full, clear

120

Res. 782

and exact description of the principle or character which distinguishes it from all other things before known, and of the usual manner of making, modifying and using the same, reference being had to the accompanying drawings.

Fig. 1. Is a view of the frame of the gas oven illustrating the design thereof.

Fig. 2. Is a view of the doors of the gas oven illustrating the design thereof.

These drawings illustrate my design for the gas oven.

What I claim as my invention is the design for gas oven, as herein above illustrated and set forth.
